(57) **CLAIM**

The ornamental design for a patient to user interface holster, as shown and described.

DESCRIPTION

FIG. 1 is a left and front side perspective view of a patient to user interface holster, which is depicted in the environment of a mobile cart;

FIG. 2 is a left and back side perspective view thereof;

FIG. 3 is a front perspective view thereof; and,

FIG. 4 is a top and front perspective view thereof.

The dash lines in the drawings depict environmental subject matter and form no part of the claimed design. The dot-dash lines depict the boundaries of the claim and form no part thereof.
